UNITED STATES PATENT OFFICE.

GERHARD MOE, OF LADYSMITH, WISCONSIN.

WIRE-CABLE-GRIPPING DEVICE.

1,218,442.

Specification of Letters Patent.

Patented Mar. 6, 1917.

Application filed October 14, 1914. Serial No. 866,665.

To all whom it may concern:

Be it known that I, GERHARD MOE, a citizen of the United States, residing at the city of Ladysmith, county of Rusk, and 5 State of Wisconsin, have invented new and useful Improvements in Wire-Cable-Gripping Devices, of which the following is a specification.

My invention relates to improvements in 10 that class of gripping devices which are adapted to be used in connection with wire cables, and it pertains more especially, among other things, to the mechanism for forcing the gripping jaws into binding contact with such cable, as the latter is being drawn forward by the gripping arms.

My invention is explained by reference to the accompanying drawings in which—

Figure 1 represents the under side of one 20 form of my device in which two movable gripping members are employed to grip the wire cable.

Fig. 2 represents the under side of another form of gripping device provided 25 with one movable gripping member.

Fig. 3 is a sectional view drawn on line X X of Fig. 2.

Fig. 4 is a detail showing a side view of 30 a part of the device shown in Fig. 2. Like parts are identified by the same reference numerals throughout the several views.

1 is a wire cable, which may be used for extracting stumps, moving automobiles, 35 boats and a variety of other purposes. When in use, one end of the cable is adapted to be attached to a movable object, the other end to a movable lever, and an intermediate portion of said cable is attached to a stationary object. The movable object is 40 adapted to be moved forwardly with a step by step movement in the ordinary way by the alternate movement of a pair of gripping members along said cable as herein- 45 after described.

The gripping mechanism is moved along the cable by the action of the arms 2, 2, and the arms 2, 2 are adapted to be pivotally connected at their opposite ends, not shown, 50 with an operating lever in the ordinary manner. By the form of gripping mechanism shown in Fig. 1, two movable gripping members 3, 3 are employed, and such gripping members are pivotally supported from

the frame 4 by the links 5, 5. The links 5, 5 are connected at one of their ends with the frame 4 by pivotal joints 6 and at their opposite ends with the grip members 3, 3, by the pivotal joints 7, 7.

When two movable links 5, 5 and two grip 60 members 3, 3 are employed, as shown in Fig. 1, the arms 2 are preferably connected with the frame 4 by a pivotal bolt or trunnion 8. When, however, I employ a single movable grip member 10 and a single link 9, 65 as shown in Fig. 2, the arms 2 are connected directly with the movable grip member 10 by the bolt or trunnion 11, as shown in Fig. 2, whereby the forward pull upon the arms 2, 2 is communicated to the gripping 70 member 10.

It will be understood that the protruding end of the grip member 10 is curved upwardly and to one side so as to be brought directly above the cable 1, as shown in Fig. 75 2, while the trunnion 8 is connected with the frame 4 directly above the cable. Referring to Fig. 2, the grip member 10 and link 9 coöperate with the stationary grip member 12, whereby as said grip member 80 10 is drawn forwardly by the action of one of the arms 2 the cable 1 is forced over against the stationary grip member 12 by the action of a movable grip member 10.

It will also be understood that the grip 85 members 10 and 12, as well as the grip members 3, are provided with spiral grooves adapted to conform in shape to and nicely fit and extend partially around the exterior surface of the cable 1, whereby as such grip 90 members are brought together they will be caused to firmly impinge the surface of said cable, whereby they are prevented from slipping thereon, as the cable is drawn forwardly by the action of the arms 2. The 95 grip mechanism comprising the gripping members 10 and 12 and link 9 are supported from the frame 4 and are retained in place in said frame by the plates 15 and 16, and said plates are secured to the frame by a 100 plurality of screws 17.

It will also be understood that the grip mechanism shown in Fig. 1 is secured to the frame 4 by the plates 18 and 19, and said plates are retained in place by a plurality of 105 screws 20.

While I have shown and described two different forms of frames and two different

2

styles of grip mechanism in Figs. 1 and 2, I wish it to be understood that the arms 2 are adapted to be used with either style, but not with both styles at the same time. 5 In both styles, however, the gripping members 3, 3 and 10 are adapted, in like manner, to impinge against the opposing surface of the cable 1, as the arms 2 are drawn forward in the act of pulling a stump or moving 10 any other object. To prevent the frame 14 from moving forward with the gripping member 10 as it might otherwise do, under some circumstances as such grip member is pulled forward by one of the arms 2, I have 15 provided a locking arm 21 which arm is pivotally connected with the frame 14 by the lug 22, and pivotal bolt 23. The arm 21 is provided with a closely fitting aperture 24 for the reception of the cable 1, whereby 20 as the locking member 10 is drawn forwardly by the action of the arm 2 the frame 14 is prevented from being moved by the friction of said gripping member 10, by the action of said arm 21, as the arm 21 is 25 caused to firmly grip the cable 1 as the frame 14 starts to move forwardly, whereby the forward movement of the frame 14 is arrested and the gripping member 10 is free to move rearwardly a slight distance in such frame, 30 as it is thrown into gripping contact with the cable 1 by the action of the link 9. By the form shown in Fig. 1 I preferably employ springs 5', 5', which springs are rigidly connected at one end to the frame 4 and 35 bear at their opposite end against the links 5, whereby said links are retained in their proper relative position to said frame and the gripping members 3.

Having thus described my invention, what I claim as new and desire to secure by Letters Patent, is—

1. In a device of the described class, the combination of a pair of movable frames, a pair of reciprocating arms respectively pivotally connected with said frames, a pair 45 of grip members located in each of said frames, a link having pivotal bearings at one end with one of said movable grip members and at its opposite end with one side of said frames, and means for retaining 50 said links and grip members in said frames.

2. In a device of the described class, the combination of a pair of reciprocating arms, a pair of movable frames, a stationary grip member and a movable grip member in each 55 of said frames, a link having pivotal bearings at one end with one of said movable grip members and at its opposite end with one of said frames, means for pivotally connecting one of said arms with one of said 60 movable grip members, means for retaining said links and grip members in said frames, an arm pivotally connected at one end with one of said frames, provided at its opposite end with an aperture for the reception of said cable, said arms being adapted to engage the cable and prevent said frames from being moved forward by the friction 65 of the grip members as the latter is brought into gripping engagement with said cable. 70

In testimony whereof I affix my signature in the presence of two witnesses.

GERHARD MOE.
